UNITED STATES PATENT OFFICE

130,944

DESIGN FOR AN ELECTRIC-SWITCH HOUSING

Homer A. Fogel, Jr., Freeport, Ill., assignor to
Micro Switch Corporation, Freeport, Ill., a cor-
poration of Illinois

Application October 23, 1940, Serial No. 96,006

Term of patent 14 years

To all whom it may concern:

Be it known that I, Homer A. Fogel, Jr., a citizen of the United States, residing at Freeport, in the county of Stephenson and State of Illinois, have invented, a new, original, and ornamental Design for Electric-Switch Housing, of which the following is a specification, reference being had to the accompanying drawing, forming part thereof, and in which:

Fig. 1 is a perspective view of an electric-switch housing showing my new design;

Fig. 2 is a side elevational view of the same housing;

Fig. 3 is an end elevational view of said housing, and,

Fig. 4 is a top plan view thereof.

I claim:

The ornamental design for an electric-switch housing, as shown.

HOMER A. FOGEL, JR.
